Primary Examiner — Jae Liang*Assistant Examiner* — Ji Sun Yoon(74) *Attorney, Agent, or Firm* — Dorsey & Whitney LLP(57) **CLAIM**

The ornamental design for a cooler, as shown and described.

DESCRIPTION

FIG. 1 is a front elevation view of a cooler showing our new design;

FIG. 2 is a left side elevation view thereof;

FIG. 3 is a rear elevation view thereof;

FIG. 4 is a right side elevation view thereof;

FIG. 5 is a top plan view thereof;

FIG. 6 is a bottom plan view thereof; and,

FIG. 7 is a front, right perspective view thereof.

The portions of the cooler shown in evenly spaced broken lines depict environmental structures that form no part of the claim.

Any combination of the illustrated features may be claimed in this application or a continuing application claiming priority to this application by converting any of the solid lines to broken lines, any of the broken lines to solid lines, or any combination thereof.
